FILM UNIT

Frank A. Zagara, Rochester, N.Y., assignor to Eastman Kodak Company, Rochester, N.Y., a corporation of New Jersey

Filed Jan. 29, 1960, Ser. No. 59,199

Term of patent 14 years

(Cl. D61—1)

FIG. 1 is a perspective view of a film unit for use in photographic copying apparatus showing my new design;

FIG. 2 is a perspective view taken from the rear thereof;

FIG. 3 is a bottom plan view; and

FIG. 4 is an enlarged fragmentary view showing the upper left corner of the left side thereof.

I claim:

The ornamental design for a film unit for use in photographic carrying apparatus as shown.
